UNITED STATES PATENT OFFICE.

JOHN F. McCANNA, OF CHICAGO, ILLINOIS, ASSIGNOR TO THE JOHN F. McCANNA COMPANY, OF CHICAGO, ILLINOIS, A CORPORATION OF ILLINOIS.

LUBRICATOR.

1,074,128.

Specification of Letters Patent. Patented Sept. 30, 1913.

Application filed October 17, 1904, Serial No. 223,701. Renewed August 10, 1910, Serial No. 576,516.

To all whom it may concern:

Be it known that I, JOHN F. McCANNA, a citizen of the United States, residing at Chicago, in the county of Cook and State of Illinois, have invented certain new and useful Improvements in Lubricators, of which the following is a specification, reference being had therein to the accompanying drawing:

10 This invention relates to improvements in that class of lubricating apparatus designed to distribute oil from a common reservoir to one or more bearings or other working parts located at different points, 15 such as the bearings and cylinders of automobile motors, engines and other mechanisms.

The invention consists of the combinations and arrangements of parts hereinafter particularly described and then pointed out in the appended claims.

In the accompanying drawings, which illustrate one embodiment of the invention, Figure 1 is a plan view of the apparatus showing the reservoir provided with four sets of pumps, the top and other parts being broken away to facilitate illustration; Fig. 2 is a section on the line 2—2 of Fig. 1; Fig. 3 is a section on the line 3—3 of Fig. 1; Fig. 4 is a vertical section of one of the pump stocks, showing the location and arrangement of the ports and valves, and taken on the line 4—4 of Fig. 5; Fig. 5 is a section on the line 5—5 of Fig. 4; Fig. 6 is a section on the line 6—6 of Fig. 4, showing the main and auxiliary pumps and the plunger operating mechanism.

Referring to the drawings 10 indicates a suitable reservoir designed to contain the lubricant and which may be of any suitable size and shape. In the present instance I have shown the same as comprising a rectangular box having a cover 11 removably secured on the top of the reservoir by screws 12. The cover 11 has a suitable filling opening closed by a screw cap 13 and under the said opening is the usual strainer 14. The reservoir 10 is also provided in one of its walls, which I shall designate the front wall, with a gage glass 15 for indicating the height of the oil in the reservoir.

Located in the reservoir 10 is a plurality

of sets of pumps, each of which comprises a primary and an auxiliary pump, as hereinafter described.

16 indicates a stock, one of which is associated with each pump set, and as shown in Figs. 2, 4 and 6, the lower end of the stock 16 is screw threaded, as at 17, and passes through an opening in the bottom of the reservoir 10, the stock being secured in position by means of a shoulder 18 on the stock within the reservoir and a clamp nut 19 screwing on the threaded end 17 against the bottom of the reservoir. The stock 16 is provided with a vertical passage 20, extending a suitable height, and adapted to discharge through the threaded end 17 into a pipe (not shown) leading to the part to be lubricated. The primary pump comprises a barrel 21 carried by or mounted on the stock 16 in any suitable manner, and extending horizontally toward the front of the reservoir, and a reciprocating plunger 22. The stock 16 is provided at its lower end with a vertical, inlet passage 23 which opens into an enlarged chamber 24, the upper end of which chamber is closed by a screw plug 25. Located in the chamber 24 is a suitable valve, such as an upwardly opening gravity valve 26, adapted to close the discharge end of the passage 23. Leading from the chamber 24 is a horizontal port 27 which communicates with the inner end of the pump barrel 21. A port 28 leads from the same end of the barrel 21, as shown in Figs. 4 and 5, and discharges into an upwardly extending passage 29, to the upper end of which is connected a vertical tube 30. The upper end of the tube 30 is bent downwardly, as at 31, so as to discharge the oil passing therethrough in drops into a pocket 32 formed in the upper end of the stock 16. Leading from the bottom of the pocket 32 is a port 33 which enters a chamber 34 in the stock 16 and is adapted to be closed by a gravity valve 35 located in the chamber 34. A screw plug 36 closes the top of the chamber 34. Leading downwardly from the chamber 34 is a passage 37 communicating with the barrel 38 of the auxiliary pump, which barrel is located above the barrel 21. A plunger 39 reciprocates in the barrel 38 and is provided on its upper side with a

groove 40, which is of such length as always to be under the discharge end of the passage 37 irrespective of the position of the plunger. A vertical port 41 in the plunger 39 communicates with the groove 40 and discharges into a channel 42 passing through the inner end of the plunger 39. A port 43 leads from the inner end of the barrel 38 into a chamber 44, in which is located a gravity valve 45 adapted to close the said port. A screw plug 46 closes the top of the chamber 44. A duct 47 extends from the chamber 44 and discharges into the passage 20. As shown, the capacity of the auxiliary pump is greater than that of the primary pump.

As shown in Figs. 2 and 4, the cover 11 is provided with an aperture 48, through which the drip tube 30 extends. The stock 16 is provided at its upper end with an annular flange 49, the inner diameter of which is substantially the same as that of the aperture 48. A collar 50, resting on the cover 11, is provided with an internal shoulder 51 having a depending annular flange 52 which extends through the aperture 48 and seats itself within the flange 49 at the upper end of the stock 16. Surrounding the tube 30 and seated upon the shoulder 51 is a disk 53 of wire gauze, or other suitable material designed to strain the oil passing from the primary pump by way of the tube 30 to the auxiliary pump. A glass cylinder 54 encloses the tube 30 and its bent end 31, and a cap 55 seated upon the upper end of the cylinder 54 is provided with a screw 56 entering a threaded aperture 57 in the bent upper end 31 and serves to clamp the sight feed glass, ring 50 and tube 30 rigidly together and secures the upper end of the stock 16. The cap 55 has an air port 58.

A common mechanism is employed for reciprocating the plungers of the primary and auxiliary pumps, and will now be explained.

Located in and extending longitudinally of the reservoir, as shown in Figs. 1 and 2, is an eccentric shaft 59. One end of the shaft 59 has a reduced threaded end 60 and is provided with a bore 61. A pinole 62, in threaded engagement with an opening in one end of the reservoir, enters the bore 61. Threaded upon the reduced end 60 of the shaft 59 is a disk 63 provided at its periphery with a recess 64 in which is pivotally mounted a spring pressed pawl 65. Located at opposite sides of the disk 63, and also threaded upon the threaded end 60 of the shaft 59, are plates 66, and located between these plates on the disk 63 is an annulus 67, the inner face of which is provided with ratchet teeth 68 adapted to coöperate with the pawl 65, while its outer face is in the form of a worm wheel 69. The opposite end of the shaft 59 is also provided with a bore into which extends a stud 70 suitably

journalled in the end of the reservoir and passing through a stuffing box 71. A set screw 72 secures the shaft to the stud 70. The outer end of the stud 71 is adapted to receive a crank 73, as shown in Fig. 1. The worm wheel 69 is engaged and driven by a worm 74, on a shaft 75, one end of which is suitably journalled in the front wall of the reservoir 10 while the other end passes through a suitable stuffing box 76 in the opposite wall and is provided with a drive wheel, such as the belt wheel 77, to which motion may be communicated from a suitable rotating part of the engine or other machine which is to be lubricated.

Extending from the stock 16 toward the front wall is an arm 78, the free end of which is bifurcated, and pivotally mounted on a horizontal pin 79 between the branches formed by the said bifurcation, is an oscillating yoke 80. The yoke 80 is removably secured to the arm 78 by means of a suitable cotter pin 81. As shown in Figs. 2 and 6, the yoke 80 straddles the eccentric shaft 59 but is open at the side adjacent the front wall of the reservoir. The yoke 80 is provided with an upwardly extending arm 82 which enters a slot 83 in the outer end of the plunger 39, the ends of the slot being tapered, as shown in Fig. 2, to reduce friction. The yoke 80 is also provided with a downwardly extending arm 84 which coöperates with a slot 85, similar to the slot 83, in the outer end of the plunger 22. While the slot 83 in the plunger 39 is of such length that the arm 82 constantly coöperates with the ends of the slot to reciprocate the said plunger 39, all lost motion being eliminated, the slot of the plunger 22 is elongated so that the arm 84 may oscillate freely in such slot without moving the plunger when the latter is held against movement at the limit of its inward movement, so as to put the pump entirely out of operation, and means are provided whereby the stroke of the plunger 22 may also be varied as desired. To this end a movable abutment is provided, and such abutment, in the present instance, takes the form of a screw 86 which is in threaded engagement with a suitable aperture in the front wall of the reservoir, a packing gland 87 being provided to prevent leakage; and the screw 86 is in line with and may be moved more or less into the path of the outer end of the plunger 22. When this screw 86 is screwed inwardly to the limit of its movement it moves the plunger 22 to the end of its discharge stroke and the arm 84 then moves freely back and forth in the slot without reacting against the ends of the slot and by adjusting the screw to intermediate positions the rate of delivery may be regulated as desired. The plunger 22 is moved on its discharge stroke by the arm 84, but is returned or moved on its suction stroke by a 130

coiled expansion spring 88 which surrounds the pump barrel 21 and reacts between the stock 16 and a collar 89 fixed on the plunger 22.

5 The operation of the device will be readily understood. Motion being imparted to the eccentric shaft 59, through the medium of the driving worm 74, turning the same continuously in one direction, the yoke 80 of 10 each set of pumps will be oscillated thereby reciprocating the plungers 22 and 39, it being obvious that by reason of the arrangement shown the said plungers will be simultaneously reciprocated in opposite directions. 15 On the suction stroke of the plunger 22 oil is drawn up from the reservoir through the passage 23 past the valve 26 and into the barrel 21. On the discharge stroke of the plunger 22 the oil is forced from the barrel 21, the valve 26 seating itself over the 20 passage 23, out the port 28 into the passage 29 and after this passage has become full the oil discharges in drops from the bent end 31 of the tube 30 into the pocket 32, and on the 25 suction stroke of the plunger 39 oil is drawn in from the pocket 32, past the valve 35 and enters the barrel 38 through the channel 42. As the barrel 38 is of greater capacity than the barrel 21, on the suction stroke of the 30 plunger 39, air is drawn in through the air port 58 and enters with the oil past the valve 35 into the pump barrel 38. On the next suction stroke of the plunger 22 the plunger 39 moving on its inward or dis- 35 charging stroke forces the oil out the port 43, past the valve 45, through the duct 47 and into the passage 20 from which it passes to the bearing or other part to be lubricated. By reason of the charge of air which is 40 drawn in by the auxiliary pump and compressed against the resistance of the valve 45, the oil is forced under the pressure of such compressed air to the bearing.

While the stroke of the plunger 39 of the 45 auxiliary pump is constant, the stroke of the plunger 22 of the primary pump may be adjusted, so that the quantity of oil fed to the auxiliary pump and consequently to the bearing, may be varied, and the rate of 50 delivery of the primary pump may be determined by the dropping of the oil from the tube 31 into the pocket 32.

The pawl 65 co-operating with ratchet teeth of the worm wheel 69 is so disposed 55 that when motion is communicated to the worm 74 by mechanism running in a forward direction the said pawl will turn the disk 63 and drive the eccentric shaft to operate the pumps. By means of this pawl 60 and ratchet connection, however, the eccentric shaft 59 may be turned independently of the worm gear 69 and its driving connection 74, for by turning the crank 73 at the end of the stud 70, the shaft may be turned 65 without affecting the worm wheel 69, as the

pawl 65 will merely run over the ratchet teeth 68. This arrangement permits of the operation of the pump by hand in order to give a preliminary lubrication to the parts when the mechanism by which motion is 70 communicated to the wheel 77, such as the motor of an automobile, is not running.

I have shown the invention in Fig. 1 as arranged for four sets of main and auxiliary pumps, but it is to be understood that 75 only one such set may be employed or any number desired. When two or more pumps are employed adjustment of the stroke of the plunger 22 of each may be effected independently of the other, in order to vary the 80 quantity of oil fed to different parts.

The apparatus may be readily disassembled for purpose of repair or cleaning, and to accomplish this it is only necessary after disconnecting the discharge pipe of 85 each pump, to unscrew the nuts 19, remove the screws 56 and the screws 12. The cover may then be lifted off, and the cotter pins 81 having been withdrawn, the yokes may be moved back in the bifurcation of the 90 arms 78 far enough to clear the eccentric shaft, when the stocks 16 with their pumps and the yokes may be easily withdrawn through the top of the reservoir.

Having described my invention what I 95 claim and desire to secure by Letters Patent of the United States, is—

1. In a lubricator, an oil reservoir, a stock mounted therein, a primary pump, means to regulate the stroke of said pump, an auxiliary pump for forcing to the part to be lubricated the oil discharged by the primary pump, and a sight-feed through which the oil passes from the primary to the auxiliary pump, said pumps and sight-feed being carried by the stock. 100

2. In a lubricator, an oil reservoir, a stock mounted therein, a primary pump on the stock, means to regulate the stroke of the said pump, a sight-feed glass on the stock, 110 a tube in the stock through which the oil passes from the pump to the sight-feed, and an auxiliary pump on the stock by which the oil is forced from the sight-feed to the part to be lubricated. 115

3. In a lubricator, an oil reservoir, a stock mounted therein, a primary pump, means to regulate the stroke of said pump, an auxiliary pump for forcing to the part to be lubricated the oil discharged by the primary 120 pump, a sight-feed through which the oil passes from the primary to the auxiliary pump, and means to operate the pumps, said operating-means, pumps and sight-feed being carried by the stock. 125

4. The combination with a lubricator comprising an oil reservoir, a primary pump, an auxiliary pump for forcing to the part to be lubricated the oil discharged by the primary pump, of actuating means consisting 130

- of an oscillating yoke having arms coöperating with the pump plungers to reciprocate the same simultaneously in opposite directions.
- 5 5. The combination with a lubricator comprising an oil reservoir, a primary pump the plunger of which is provided with an elongated slot, and an auxiliary pump for forcing to the part to be lubricated the oil 10 charged by the primary pump and whose plunger is also provided with a slot, a sight feed device through which the oil passes from the primary pump to the auxiliary pump, of actuating means consisting of a 15 pivoted yoke having arms one of which enters the slot of each pump plunger, a spring moving the primary pump plunger outwardly, and an adjustable abutment located in the path of the latter plunger.
- 20 6. In a lubricator, the combination with a reservoir, of a pair of pumps of different capacities, means for reciprocating the pump plungers simultaneously in opposite directions, means for varying the rate of delivery of the pump of lesser capacity, and a 25 connection through which the oil passes

from the latter pump to the other pump, such connection having an air inlet.

7. In a lubricator, the combination with a reservoir, of a pair of coöperating pumps 30 therein, an eccentric located in the reservoir, a yoke oscillated by the eccentric and having a pair of opposite arms coöperating with the pump plungers, and an adjustable abutment to regulate the stroke of one of 35 the pumps.

8. In a lubricator, the combination with a reservoir, of a pair of horizontally disposed valved pumps therein, an eccentric, a pivoted yoke oscillated by the eccentric and having oppositely extending arms coöperating 40 with the pump plungers, a connection through which the oil passes from one pump to the other, and means for varying the rate of delivery of one of the pumps. 45

In testimony whereof I affix my signature in presence of two witnesses.

JOHN F. McCANNA.
